UNITED STATES PATENT OFFICE.

JOSEPH S. MITCHELL, OF CHICAGO, ILLINOIS, ASSIGNOR TO SULLIVAN MACHINERY COMPANY, A CORPORATION OF MASSACHUSETTS.

CORE DRILL.

Application filed November 5, 1923. Serial No. 672,795.

My invention relates to core drills.

It has for its object to provide an improved core barrel and more particularly an improved core barrel having an improved 5 connection to the core barrel head whereby the threaded connections and the necessary weakening resulting therefrom is eliminated. A further object of my invention is to provide an improved method of making core barrels whereby the above objects are obtained.

In the accompanying drawings I have shown for purposes of illustration one form which my invention may assume in practice.

In these drawings,—

Fig. 1 is a side elevation of a core barrel constructed in accordance with my improvement.

Fig. 2 is a partial vertical sectional view showing my improved connection of the barrel tubing to the head.

In this illustrative construction I have shown a core barrel of a standard construction used in oil well work, which need not be more specifically described than to say that it comprises a fluted diamond bit 1 and fluted guide 2 operatively connected to the core barrel tubing 3, this tubing 3 in turn being connected to the core barrel head 4 in an improved manner hereinafter described.

In my improved construction the end of the core barrel tubing 3 is turned to a driving fit as shown at 5 and a groove 6 is formed in the head 4 at a point intermediate the ends thereof and preferably at the inner end of a reduced portion 7 below its usual threaded portion 8 and adjacent a portion turned to correspond to the portion 5 of the barrel. Then the head is driven into the turned end of the barrel, the upper end of the tubing 3 is peened into the groove in the head, and the groove, made by the peening in the member 3 and by the adjacent shoulder on the head, is filled with welding material, and the whole welded. In a preferred form, to prevent relative rotation a plurality of transverse drill holes 9 is also provided through the member 3 and part way through the portion 7 of the member 4, as indicated, below the peening, and these holes are likewise filled with welding material before welding.

As a result of my improved construction it will be observed that all threading between

the core barrel tubing and the core barrel head is eliminated with a resultant elimination of the weakening due to the necessary cutting away of the metal in threading, and a consequent elimination of the breaking of 60 the core barrel at this joint, a construction being produced in which there is more metal and therefore more strength at the joint than at any other part, this at the same time that the desired uniform external diameter is 65 maintained, the use of the welding material tending to produce an entirely smooth exterior.

While I have in this application specifically described one form which my invention may assume in practice, it will be understood that this form of the same is shown for purposes of illustration and that the invention may be modified and embodied in various other forms without departing from 75 its spirit or the scope of the appended claims.

What I claim as new and desire to secure by Letters Patent is:

1. A core barrel comprising a head forming a drill rod connection and having a circumferentially extending groove formed on the periphery thereof, and a plurality of recesses, a tubular core receiving barrel member having a drive fit with said head and 80 having its extremity adjacent said head peened into said groove partially filling the latter, said barrel member having perforations in registry with said recesses, and bodies of metal in the unfilled portion of 85 said groove and in said perforations and recesses and welded to the adjacent portions of said head and barrel member respectively.

2. A core barrel comprising a head forming a drill rod connection, said head having a shoulder, a circumferentially extending groove formed on the periphery thereof adjacent said shoulder, and a recess, a tubular core receiving barrel member fitting said head, the extremity of said barrel member adjacent said shoulder being peened into 95 said groove partially filling the latter, and a perforation in said barrel member in registry with said recess, and bodies of metal in the unfilled portion of said groove and in 100 said perforation and recess and welded to the adjacent portions of said head and said barrel member respectively.

3. A core barrel comprising a head forming a drill rod connection and having a 110

shoulder, a reduced portion, said reduced portion having recesses formed therein, and a circumferentially extending groove formed on the periphery of said reduced portion 5 adjacent said shoulder, a tubular core receiving barrel member having a drive fit with said reduced portion and its extremity adjacent said shoulder peened into said groove partially filling the latter, and perforations formed in said barrel member in registry with said recesses, and bodies of metal in the unfilled portion of said groove and in said perforations and recesses and welded to the adjacent portions of said head 10 and barrel member respectively.

4. A core barrel comprising a head forming a drill rod connection and having an enlarged internally threaded portion and a re-

duced portion, said reduced portion having recesses formed therein, and a circumferentially extending groove formed on the periphery of said reduced portion adjacent the lower end of said threaded enlarged portion, a tubular core receiving barrel member having a drive fit with said reduced portion and having its extremity adjacent the lower end of said enlarged portion peened into said groove partially filling the latter, said barrel member having perforations in registry with said recesses, and bodies of metal in the unfilled portion of said groove and in said perforations and recesses and welded to the adjacent portions of said head and barrel member respectively. 20 25 30

In testimony whereof I affix my signature.
JOSEPH S. MITCHELL.
